UNITED STATES PATENT OFFICE.

ROWLAND VILLAGE, OF ECCLESALL, SHEFFIELD, ENGLAND.

MOLD FOR INGOTS AND OTHER HEAVY STEEL CASTINGS.

1,388,534.

Specification of Letters Patent. Patented Aug. 23, 1921.

Application filed January 26, 1921. Serial No. 440,094.

To all whom it may concern:

Be it known that I, ROWLAND VILLAGE, a subject of the King of England, residing at 76 Banner Cross road, Ecclesall, Sheffield, 5 England, have invented certain new and useful Improvements in or Relating to Molds for Ingots and other Heavy Steel Castings, of which the following is a specification, reference being had therein to the accompanying drawing.

This invention relates to molds for ingots and other heavy steel castings, its object being to provide for them an improved construction of feeder-head of the type comprising an annular fire-place around a central feed opening which has been used with or without a blow pipe action to apply additional heat to the metal at the top of the mold during and after casting for the purpose of keeping it liquid while the main body of the metal solidifies in order to reduce the size of the cavity or "pipe" at the upper end of the ingot or casting. According to the present invention a detachable 15 annular fireplace is provided with inner walls, to extend the mold feed opening, which are made removable with the fireplace and are formed with undercut projections to secure a renewable refractory lining inside the 20 feed opening. The joint between these inner walls and the mold may either be protected with refractory cement or may be formed by an annular fire-brick engaging the mold feed opening in a similar manner to that 25 of the usual feeder tubes and also engaging the feeder head or fire-place, being secured to the latter in sections by engaging projections and recesses and by refractory cement.

The inner walls of the fire-place or feeder 30 head according to the present invention are also preferably so disposed that the central feed opening is of less area at the top than at the bottom, in order to assist in radiating and reflecting heat down to the metal at 35 the top of the mold and to facilitate removal of the feeder-head from the solidified metal.

In the accompanying drawings:—

Figure 1 is a central section and

Fig. 2 is a plan of a feeder-head according 50 to the present invention.

Fig. 3 is an elevation of the feeder-head in place on an ingot mold.

Like reference figures indicate like parts throughout the drawings.

55 A feeder-head according to the present in-

vention is conveniently made of cast iron and is in the form of an annular detachable fire-place as seen clearly in Figs. 1 and 2, its inner walls 1 being integral with or secured to the remainder of the fire-place and 60 inclosing a central opening which forms an extension of the mold feed opening when the feeder head is in position. The walls 1 are inclined as shown in order that the central opening may be of less area at the top than 65 at the bottom where it joins the mold feed opening, in order to assist in radiating and reflecting heat down to the metal at the top of the mold and to facilitate removal of the feeder-head from the solidified metal. The 70 outer walls 2 of the annular fire-place are provided with openings 3 supplying a proportion of the air required for combustion to the fuel in the annular space 4 between the walls 1 and 2.

The base of the fire-place is comprised by fire-bars 5 which are preferably renewable. In the construction illustrated the inner walls 1 comprise a four sided truncated pyramid while the outer wall 2 is in the 80 form of a cylinder, the fire-bars 5 being made in four detachable sections which may easily be lifted out of the fire-place between arms 6 which connect the upper edges of the walls 1 and 2. It will be understood however, that 85 the outer wall may, if desired, conform in shape to the inner walls 1. A detachable annular cover plate may be provided for the top of the fire-place to prevent molten metal accidentally falling on to the fuel 90 therein. The cover plate would be made with one or more apertures for the exit of the products of combustion.

An annular fire-brick 7 is secured to the wider part of the central opening so as to 95 project out therefrom and form a flange 8 to engage the mold feed opening or a recess around it. Preferably this fire-brick 7 is made in sections and is secured in place by projections 9 on the feeder-head engaging 100 recesses in the brick sections, a refractory cement or the like being used to form a joint between the ends of the brick sections. The flange 8 formed by the projecting fire-brick 7 fits into the mold feed opening or into a 105 recess around it and is designed to come into sufficiently close contact with the mold to provide a seal between the mold and the feeder-head, thus preventing the escape of molten metal between feeder-head and mold. 110

The remainder of the central opening is provided with undercut projections 10 or the like on the inner walls 1 to hold in place a renewable refractory lining 11 which is applied in a plastic condition. A plastic mixture of fire-clay, graphite and ganister is conveniently used both to provide the lining and as a cement for the sections of the fire-brick.

If desired the sectional fire-brick 7 may be omitted, the joint between the feeder-head and the mold being protected by refractory cement or the like applied after the feeder-head has been placed in position.

The feeder-head is furnished with a base 15 or feet 12 to rest on the mold around its feed opening and with a space 13 below the fire-bars 5, which space has an opening or openings 14 to the outside of the feeder head whereby air for combustion may obtain access to the fuel in the space 4 by way of the space 13 through the fire-bars 5. The space 13 with its openings also provides means for clearing the fire by a poker or the like.

If desired air or gas under pressure may 25 be supplied to the space 13 through one of its openings 14 in the outer side of the feeder-head. In this case the other openings would preferably be closed, and when a cover plate is used the aperture therein would preferably 30 be arranged as far as possible from the opening through which the air or gas under pressure is applied.

Holes 15 are preferably provided in the 35 ends of the arms 6 for the insertion of pins or the like by means of which the feeder-head may be lifted, removed from the mold when the metal has solidified and be replaced on another mold ready for another cast after the lining 11 has been renewed if necessary. 40 The top of the mold is preferably heated before the steel is cast and maintained hot until, during and after casting by the feeder-head hereinbefore described. In this way ingots and other heavy steel castings may be 45 made practically free from "pipe" whether the main feed of the mold is from the top or

from the bottom with a minimum of extra labor and time.

What I claim is:—

1. The combination with a mold for ingots 50 and other heavy castings of a feeder head in the form of a detachable annular fire-place whose inner walls to extend the mold feed opening are integral with the fire-place, and are formed with undercut projections securing 55 a renewable refractory lining inside the central opening of the feeder head, substantially as specified.

2. The combination with a mold for ingots and other heavy castings of a feeder head in 60 the form of a detachable annular fire-place whose inner walls to extend the mold feed opening are integral with the fire-place and are formed with undercut projections securing 65 a renewable refractory lining inside the central opening of the feeder-head and an annular fire-brick engaging both the feeder-head and the mold feed opening and secured to the feeder head in sections by engaging 70 projections and recesses and by refractory cement substantially as specified.

3. The combination with a mold for ingots and other heavy castings of a feeder head in the form of a detachable annular fireplace whose inner walls to extend the mold feed 75 opening are integral with the fire-place and are formed with undercut projections securing a renewable refractory lining inside the central opening of the feeder-head which is of less area at the top than at the bottom 80 and an annular fire-brick engaging both the feeder-head and the mold feed opening and secured to the feeder-head in sections by engaging 85 projections and recesses and by refractory cement, substantially as specified.

In testimony whereof I have signed my name to this specification in the presence of two subscribing witnesses.

ROWLAND VILLAGE.
